UNITED STATES PATENT OFFICE.

HUGH JOHNSTON, OF TORONTO, ONTARIO, CANADA.

SCREEN.

1,245,237.

Specification of Letters Patent.

Patented Nov. 6, 1917.

Application filed July 1, 1916. Serial No. 107,165.

To all whom it may concern:

Be it known that I, HUGH JOHNSTON, a subject of the King of Great Britain, and resident of 55 Radford avenue, in the city 5 of Toronto, county of York, Province of Ontario, Dominion of Canada, have invented certain new and useful Improvements in Screens, of which the following is a specification.

10 The invention relates to improvements in screens as described in the present specification and shown in the accompanying drawings that form part of the same.

The invention consists essentially in the 15 novel construction and arrangement of parts, whereby a curtain may extend continuously throughout the several sections of the screen.

The objects of the invention are to devise 20 a screen easy to move and readily collapsible and which may be set up with a single piece of material preferably cut specially to fit the various parts of the screen without being separated therefore forming an individual element that can be replaced and repaired with facility, to furnish a screen that is particularly applicable to screening beds in hospitals and sick rooms and generally to provide a neat, cheap, durable and 25 serviceable screen.

In the drawings, Figure 1 is a perspective view of the screen as it appears when extended and with the curtain removed.

Fig. 2 is a perspective view of the screen 30 extended and showing the curtain in position thereon.

Fig. 3 is a side view of the screen in its folded position.

Fig. 4 is a detail of the curtain rod used 40 on the main frame.

Fig. 5 is a detail of the curtain rod used on the upper end of the wings.

Fig. 6 is a detail of the vertical curtain rod used on the outer ends of the wings.

45 Fig. 7 is a detail of the locking collar used to hold the lower horizontal curtain rod in position in the main frame.

Fig. 8 is a detail of one of the supporting brackets for the vertical curtain rods.

Fig. 9 is a detail of one of the pierced knobs.

Fig. 10 is a detail of one of the rotatable collars mounted on the main frame and adapted to receive a horizontal curtain rod from the wings.

Like numerals of reference indicate corresponding parts in each figure.

Referring to the drawings, the main frame, which is formed of the uprights 1 and 2, preferably tubular, the upper tubular rail 3 and the lower tubular rails 4 and 5, is supported by the caster stands 6, the latter being in the form of bars having the central sockets 7 encircling the uprights 1 and 2 between the lower rails 4 and 5 and the end 65 sockets 8 receiving the shanks of the rubber tired casters 9.

The main wings of the screen are formed of the lower tubular rails 10 extending from the sockets 11 rotatably mounted on the uprights 1 and 2 above the rails 4, the upper tubular rails 12 extending from the sockets 13 rotatably mounted on the uprights 1 and 2 above the rails 3, and the uprights 14 carrying the fixed sockets 15 for receiving the 75 other ends of the rails 10 and 12, said uprights 14 standing on the rubber tired casters 16.

The tubular rails 12 support the extension rods 17 therein, said rods 17 being telescopically arranged within said rails 12 and having the knobs 18 screw threaded onto the ends.

The extension rods 17 project from the sockets 19 extending from the sleeves on the 85 uprights to which the upper sockets 15 are secured or form part therewith.

20 is a bracket rigidly mounted on the rod 4 intermediate of the length thereof and projecting outwardly from each side of said 90 rod and forming a stand for the main wings when folded one on each side of the main frame.

21 are rods forming horizontal curtain supports between the uprights 1 and 14 95 and the uprights 2 and 14 at the upper ends thereof, said rods having their ends curled backwardly and forming the circular open-

ings 22 adapted to register with the openings in the ends of said uprights and being held in position on said uprights by headed pins 23 extending through the openings 22 5 and entering the said uprights.

24 is a rod extending from the upright 1 to the upright 2 and having its ends offset and supported in the openings 25 in the headed pins 23, said rod forming a horizontal curtain support between said uprights and completing with the rods 21 and the extension rods 17 a series of curtain supports throughout the upper part of the several sections of the screen.

15 26 are curtain rods having their curved ends 27 mounted on the top ends of the uprights 14 and held thereon by the pins 23 and extending downwardly parallel with said uprights and being supported at their 20 lower ends in slots 28 in the brackets 29 mounted on said uprights above the sockets 15.

30 is a horizontal curtain rod connecting the uprights 1 and 2 above the sockets 11 25 and being supported in slots in each of said uprights.

The rod 30 is held non-rotative in said slots by means of a sliding collar 31 encircling each of the uprights 1 and 2 above 30 said rod and having the pins 32 extending downwardly therefrom and engaging suitable openings in said rod.

33 are horizontal curtain rods extending from the uprights 1 and 2 respectively to 35 uprights 14, said rods being supported at one of their ends in suitable openings in said uprights 14 and at their other ends being supported in the substantially key shaped slots 34 of the sockets 35 rotatably 40 mounted on the uprights 1 and 2.

In the operation of this invention the various rods are threaded through the curtain 36 which has previously been cut and sewn to the proper form and the said rods 45 are then secured in their respective positions on the main and wing frames. When the extension rods 17 are not required they are simply pushed into the rods 12, the portion of curtain supported thereon folding in vertical position against the uprights 14.

Owing to the wing frames being rotatively mounted on the main frame they may be moved on the casters 16 to any desired 55 position according to the object to be screened.

When it is desired to move the screen from one place to another wing frames may be folded one on each side of the main 60 frame and raised slightly to rest on the stand 20 of said main frame and the whole device may be wheeled to the desired position on the casters 9.

It will thus be seen that an efficient form of screen is provided which may be operated with ease by one person and which may be collapsed to occupy a very small space when not in use. 65

What I claim is:

1. A screen comprising a curtain, a central frame and an end frame swinging from said central frame, the top rails of said frames forming removable curtain hangers and supporting said curtain at substantially an even height throughout the length of the 75 screen.

2. A screen comprising a curtain, a central frame, end frames swinging from the uprights of said central frame, said frames having removable top rails threaded through 80 said curtain and supporting the latter at an even height throughout the length of the screen, and extension rods from said end frames forming supports for the continuing portions of said curtain. 85

3. In a screen, a main frame having uprights and cross rails, wing frames, each having an upright and cross rails secured by rotative members to said uprights of the main frame, knobs secured to said uprights having rod holes, vertical curtain rods having an eye at their upper ends engaged by the knobs of said wing frames and brackets secured to wing frame uprights and receiving the lower ends of said vertical rods. 90

4. In a screen, a main frame having upright and cross rails, one of said cross rails being at the bottom, another slightly thereabove and another adjacent to the top, caster 100 stands secured to said uprights between the lower rails, casters carried by said stands, wing frames, each having an upright and cross rails secured by rotative members to said uprights of the main frame, a bracket 105 secured on one of the horizontal lower rods of said main frame and forming a support for said wing frames when folded against said main frame and horizontal and vertical curtain supports removably secured in said 110 main frame and said wing frames and a curtain carried by said supports.

5. In a screen, a main frame having upright and cross rails, one of said cross rails being at the bottom, another slightly thereabove and another adjacent to the top, caster stands secured to said uprights between the lower rails, casters carried by said stands, wing frames, each having an upright and cross rails secured by rotative members to 120 said uprights of the main frame, extension rods extending from said wing frames at each end, curtain rods removably secured on the upper ends of said uprights by knobs having shanks entering said uprights 125 through said rods, a curtain rod mounted

in sockets in the knobs in the uprights of said main frame, a horizontal curtain rod mounted in the uprights of said main frame adjacent the lower ends thereof, collars 5 loosely encircling the last named uprights and having pin projections therefrom entering slots in said lower horizontal curtain rod, curtain rods mounted in slots in the uprights of said wing frames and in rota-

tive members encircling the uprights of 10 said main frame and a curtain supported by said rods and by said extension rods.

Signed at the city of Toronto, Province of Ontario, this 21st day of June, 1916.

HUGH JOHNSTON.
